APPARATUS FOR EQUALIZING THE PRESSURE DIFFERENTIAL BETWEEN THE INTERIOR AND EXTERIOR OF A PLUGGED TUBING STRING
Horace L. Courtney, Victoria, Tex., assignor to Completion Tools, Inc., Victoria, Tex., a corporation of Texas
Filed Mar. 28, 1958, Ser. No. 724,590
18 Claims. (Cl. 166—152)

This invention relates to the completion of wells and more particularly to tools for testing and completing wells. This application is a continuation in part of my co-pending applications, Serial Nos. 514,939, now abandoned; 448,418, now abandoned, and 448,419 abandoned or forfeited.

It is an object of this invention to provide a well tool which is closed to well fluids during running in with valve means for equalizing pressure at the bottom end of the tubing upon downward movement of the tubing relative to a part anchored to the wall of the well.

Another object is to provide a well tool for completing wells suspended from a tubing string and run with any desired fluid cushion and in which the pressure differential between tubing pressure and well pressure is equalized during setting of the production packer.

Another object is to provide an apparatus for perforating a selected formulation under atmospheric plus a predetermined additional pressure while isolating the column of fluid in the well from the formation and thereafter producing the formation through a full open tubing.

Another object is to provide a well completion tool adapted to be run with any desired water cushion in a closed production tubing, which tool will equalize pressure between the formation to be tested and the tubing bore by movement of the tool relative to the production packer to test the casing seal and thereafter provide a full open bore through the tool for running a perforating gun and for producing the perforated formation.

Another object is to provide a testing and production tool adapted to be run on the production tubing, which is either dry or provided with a desired water cushion, which will test the casing seal, permit squeeze cementing if the casing seal is imperfect, thereafter test the re-cemented casing seal, and then permit perforation and production through a full open bore.

Another object is to test a casing seal and then to perforate the desired formation and after perforation to leave the test packer in the hole to thereby eliminate dropping the column of mud back on the formation and to reduce the number of times the tubing must be run.

Another object is to provide a well completion apparatus which permits testing of the casing seal and isolates the column of mud from the producing formation while it is being perforated and produced with a single run of the production tubing.

Other objects, features and advantages of the invention will be apparent from the drawings, the specification and the claims.

In the drawings wherein there are shown illustrative embodiments of this invention and wherein like reference numerals indicate like parts:

FIGURE 1 is a schematic illustration of a well tool embodying this invention with the parts shown in the position they assume while the tool is being run into the well;

FIGURE 12 is a view along the lines 12—12 of FIGURE 11; and

FIGURE 13 is a view along the lines 13—13 of FIGURE 11.

30 Referring first to FIGURES 1 through 7, the invention is illustrated in a tool which includes a conventional hook wall packer 10 which is set by downward movement of the mandrel 19 relative to the remainder of the packer in the conventional manner. A valve assembly 11 which depends from the packer is actuated in the last stages of setting packer 10. While the tool is shown as including a packer, it will be appreciated that the packer is of conventional construction and the invention in this form of tool resides in the remainder of

35 the tool (the valve assembly) and the combination of the valve assembly with a packer in such a manner that the valve assembly is opened as the packer is set. Of course, the valve assembly may be operated by any means which will hook on to the wall and as shown in the modified form of tool, the valve assembly may be opened as it seats in a previously landed packer which forms a part of the tool.

The tubing 12 from which the tool is suspended may be run dry or with any desired water cushion. When the

50 proper depth is reached, the tubing string is manipulated in the conventional manner to release the J-slot 13 and commence setting of packer 10. Upon release of the J-slot 13, the slip expander 14 expands slips 15 into engagement with casing 16. Thereafter the annular packer expander 17 expands the packer rubber 18 to seal between the casing and mandrel 19. The packer will then function as a production packer. Shoulder 9 on mandrel 19 will withdraw the expander from behind the slips 15 if it desired to remove the packer.

55 During the last increment of movement of the mandrel 19 relative to the remainder of packer 10, the valve assembly 11 is operated to open the valve and equalize pressure between the open hole below the packer 10 and the interior of mandrel 19.

60 At this time some of the fluid within the open hole will flow into the tubing and the formation to be produced will be isolated from the column of drilling fluid in the casing-tubing annulus above the production packer 10.

65 In accordance with the usual practice, the casing 16 will have been cemented in the well by forcing cement down through the casing and up the annulus between the

well bore and the exterior of the casing. If this casing seal is complete, the water sands above the formation to be produced will have been isolated and there will be no flow into the tubing after equalization of pressure within and without the tubing by opening valve 11. However, if the water sands are not completely isolated, water will flow into the tubing and indicate that the casing should be recemented. Water flow may reach the surface or the level of fluid within the tubing may be determined in any desired manner.

After it is determined that the water seal is holding, a perforating gun 21 may be run through the tubing as illustrated in FIGURE 4 and utilized to knock out a plug 22 in the bottom of the mandrel. This plug is provided with a suitable seal, such as O-ring 23 (FIG. 3) to seal the lower end of the mandrel, and the plug is held within the bottom of the mandrel 19 by friction. After the plug has been knocked out from the bottom of the tubing, a full open bore is provided through the mandrel 19 to permit passage of the perforating gun 21. Subsequently the formation is perforated by gun 21 and the formation produced through a full open hole provided by mandrel 19.

In FIGURE 5 the perforating gun 21 is shown to have perforated the formation and flow to have commenced from the formation upwardly through the mandrel 19.

It will be appreciated that if the casing seal is defective the tool may be removed from the well merely by pulling the tubing which will release the packer 10. Thereafter conventional methods may be utilized to recement the casing, and the tool of this invention may be run to again test the casing seal. As an alternative squeeze cementing may be carried out through the tubing and mandrel in the conventional manner. After recementing, the tubing may be swabbed to test the seal.

Referring now to FIGURES 3, 6 and 7, the details of the particular valve assembly utilized in this form of the invention are illustrated.

To accomplish the method of operation previously outlined it is necessary to provide a well tubing closed to well fluids during running of the tool and then provide a full open tubing. The full open tubing is permitted by removal of plug 22 previously referred to.

In order to remove the plug 22 against the hydraulic lock that will be present, it is necessary to first equalize pressure across the plug. This is accomplished by the valve assembly 11.

To maintain the full open bore characteristic of this invention, the mandrel 19 has formed therewith a valve support 24 in which the valves are mounted. A duct 25 is provided which opens at its inner end 25a into the bore of the mandrel 19 and terminates at its outer end 25b in a valve seat which is exposed to well fluids below the production packer. A valve member 26 controls flow of fluid through duct 25.

Operation of the valve member is controlled by manipulation of the mandrel relative to a part held stationary by engagement with the casing wall, such as the slips 15 of the packer 10. As above noted, this control of the valve 26 preferably occurs in the last stages of setting the packer 10. Such control may be provided by a member such as the resiliently loaded actuator bar 27 secured to and maintaining the valve 26 in closed position and means such as the end 28 of cage 29 engaging the actuator bars 27 and overcoming their restraining or seating action on the valve 26 to permit the valve 26 to unseat. Each bar 27 is resiliently loaded by a spring 62 compressed between an enlargement 27a on bar 27 and valve support 24. While any desired means of holding the valve 26 on its seat which may be overcome by the engagement with the member carried by the slips, such as cage end 28, may be used, actuator bar 27 is preferred.

It will also be appreciated that while the actuator bar 27 is shown to be integral with the valve 26 and valve stem 31, this is for convenience of construction only.

The cage 29 protects the valve assembly and prevents premature unseating of valves 26 while the tool is being run in the hole. As shown in FIGURE 1, the cage is carried by the friction members 20 which are in turn carried by slips 15.

It has been found that a valve having a large area subject to the pressure differential across the mandrel 19 will resist operation of a valve member. It is, therefore, desired to make the valve seats 25b of small size so that the force necessary to unseat the valve 26 will be relatively small.

As a further aid in avoiding difficulty in unseating valve 26 due to a hydraulic lock, the valve may be provided with means for counterbalancing the effect of open-hole pressure. In the form illustrated in FIGURE 3 the combination actuator rod 27 and valve stem 31 extend through the valve support 24, and a suitable sliding seal such as O-ring 32 is provided between the actuator rod and valve support. As the cross-sectional area of the bore through valve support 24 where it is engaged by seal 32 is approximately equal to the area of valve seat 25b, there is provided an equal and opposite pressure responsive member connected to the valve member 26, and the effect of open-hole pressure on the valve member is substantially balanced out.

One or more valves of the type just described may be used. In the illustrated embodiment two such valves appear, and it will be understood that the preceding discussion applies to both of such valves.

30 It is believed that the operation of the complete tool is apparent from the foregoing, but it will be summarized here for convenience. The complete tool is made up on a conventional tubing string and run in a cased well filled with the desired amount of water or oil fluid cushion. 35 At the desired depth the packer 10 is set in the conventional manner by manipulating J-slot lug 13a to permit slip expander 14 to expand slips 15 into engagement with the casing. Thereafter the packer expander 17 expands packer 18 to seal the tubing-casing annulus. In 40 the last stages of expansion of packer rubber 18, the abutment member 28 contacts the heads of valve actuators 27 to unseat valves 26. This permits equalization of pressure across plug 22 in the bottom of the mandrel 19. At this time the well test previously described is 45 conducted. Thereafter plug 22 may be removed and the well perforated in the conventional manner as shown in FIGURE 5. The perforating gun 21 then may be removed and the well will flow in the usual manner through the mandrel 19 and tubing 12 to the surface.

50 Referring now to FIGURES 8 through 13 there is shown a form of this invention in which the production packer is of the type which is landed in the well before the tubing string is run.

The packer 30 may be of any desired type which 55 is run and set in the well on either a string or a wire line. Preferably in practicing this invention the packer is run and set with a wire line. For illustration of the type of packer utilized in this form of the invention, see Composite Catalog of Oil Field Equipment and Services, 60 22nd edition, pages 590 and 612. It will be apparent that this packer would need be modified to provide an actuating shoulder 34 such as shown in the drawings of this application.

After the wire line packer is run and set in the well in 65 the conventional manner, the remainder of the tool is made up on the lower end of tubing string 12 and run into the well. This remainder of the tool is indicated generally at 35.

In order to run the string either dry or with a desired 70 water cushion as contemplated by this invention, the plug 22 is positioned in the lower end of mandrel 36.

As the portion 35 of the tool moves into contact with the packer 30, the tailpipe provided by the lower portion of mandrel 36 moves through packer 30 and the valve assembly 37 moves into the upper end of the packer.

Seal means are provided on either the packer or the valve assembly for sealing between the assembly and packer when the assembly is fully landed. If desired, this seal means may be provided by a suitable seal 38 carried on the periphery of the valve assembly and a suitable seal 39 within the bore of the packer 30. Once this seal means is operative, the well bore below the packer 30 is isolated from the well bore above the packer.

As the seal means previously referred to becomes operative but before the assembly 35 is seated within the packer, the valve actuator 41 which is integral with valve member 42 and extends through duct 45 in valve support 53 engages abutment or shoulder 34 within the packer to unseat valve 42 which is provided at the inlet end of duct 45. This permits equalization of pressure between the interior of the production string 12 and the well below production packer 30. Well fluid from below the packer passes upwardly through the annulus surrounding tailpipe 36 to the assembly 35. This fluid then passes through a plurality of passageways 43 through valve support 53 to a gathering ring or annulus 44 to which the valve 42 is exposed. Annulus 44 is provided by a counter bore in body member 64 immediately above the threaded connection between the body 64 and valve support 53. The fluid passes the open valve 42 and travels through duct 45 to the interior of mandrel 36 to equalize pressure across the plug 22 in the lower end of the mandrel.

As in the case of the previously described embodiment, the actuator 41 is resiliently loaded by spring 46 compressed between valve support 53 and an enlargement 41a on actuator 41 to hold the valve in closed position while running. The forces across valve 42 are also counterbalanced by an equal and opposite force acting on seal 47 on the actuator over an area defined by seal 47 in the manner heretofore explained.

After valve 42 is unseated, the left-handed helical slips 48, 49 and 51 carried by the valve support 53 are landed in the left-handed threads 52 in the upper end of production packer 30. These slips are segments formed in the conventional manner with their lower flanks inclined upwardly and their upward flanks extending perpendicular to mandrel 36. With this arrangement, the slip segments will slide down over the teeth of threads 52 but will hold against an upward pull. Of course the teeth can be disengaged by right-hand rotation of tubing 12. The lock-down feature provided by the slips permits pressure to be applied to the producing formation through the production string in the conventional manner to squeeze, sand frac, etc.

After the pressure is equalized across plug 22 and the slips fully seated within threads 52, the well may be tested, the plug 22 knocked out and the well perforated and produced in the manner heretofore explained in conjunction with the previously described embodiment of this invention.

It is contemplated that it may be desirable at some time to pull the tubing string and that at such time there may be a hydraulic lock across threads 52, that is between pressure above and below production packer 30 and acting on the seal means 38 and 39 to cause difficulty in releasing the slips. For this reason there is provided a means for equalizing the pressure above and below the production packer at the will of the operator. As the tubing may be raised even against such hydraulic lock, it is preferred to provide a valve support 53 which is slidable on mandrel 36. This will necessitate the annular seals such as those provided by seals 54, 55 and 56 in body 64 to confine fluid flow through the valve assembly and into mandrel 36 when pressure across knockout plug 22 is being equalized. One or more ears 57 should also be carried by mandrel 36 above the valve assembly to force the valve assembly down into the packer.

To provide for relief of any hydraulic lock across the

5 packer, the mandrel may be provided with one or more ports 58 above the dual seal 56. A second seal provided by seal means 59 is provided above the ports 58 so that the seals 56 and 59 isolate ports 58. It will be recognized that the above-described structure provides a sliding valve between the mandrel and valve support 53. Thus upon an upward pull being exerted on production tubing 12, the ports 58 will be raised past the upper seal 59, and pressure will be equalized through these ports to remove any hydraulic lock across seals 38 and 39. Thereafter the tubing may be rotated in clockwise manner to release the slips from threads 52 in the packer.

10 To avoid premature exposure of ports 58, the body 64 is preferably pinned to the ears 57 with one or more shear pins 61. These pins may be sheared by the downward force of production tubing when the assembly is seated in the packer. If not sheared at this time, they will be sheared when the production string is pulled in the manner just explained.

15 To maintain the body 64 and valve support 53 on the mandrel after pins 61 have been sheared, a lug 62 is provided on the mandrel and below valve support 53. The valve support engages this lug in the manner shown in FIGURE 10 when the production tubing is pulled from the well.

20 The operation of the tool shown in FIGURES 8 through 13 is believed apparent from the above but will be summarized here for convenience. The packer 30 is first run in and set in the casing above the formation to be produced, preferably on a wire line.

25 The tool 35 is then made up on the production string and run into the well and seated within the production packer as shown in FIGURE 9. At this time the casing seal is tested in the manner previously explained.

30 If the casing seal is satisfactory, a perforating gun such as shown in FIGURE 5 is run through the production tubing and the plug 22 knocked out of the lower end of mandrel 36. The formation zone 63 is then perforated and produced through mandrel 36 and production tubing 12 in the conventional manner.

35 Inasmuch as a full open tubing is provided, it will be appreciated that various procedures may be carried out in well completion and workover. Where these procedures cannot be completed without circulation in the tubing-casing annulus, it will be apparent that the valve support may be released from the packer to permit such circulation. Thereafter the valve support may be again seated in the packer and the annulus above and below the packer will be effectively separated.

40 In releasing the assembly 35 from the packer, the production tubing 12 is first raised to expose ports 58 and equalize pressure across packer 30. Thereafter, the string is lowered until the ears 57 rest on the valve support. Righthand rotation of the tubing string will engage the ears with the upstanding portion of the valve support to which the ears were previously pinned. Continued rotation of the mandrel will release the valve support from threads 52 and the assembly 35 may be pulled out of the packer in the manner illustrated in FIGURE 10.

45 50 55 60 65 70 Of course it will be apparent that with either form of tool the producing formation could first be perforated by running a gun in the open casing and thereafter the tool of this invention used to cause the formation perforated to commence flowing with substantially atmospheric pressure and thereby eliminate swabbing the well in. In other words, the formation would be brought in by subjecting it to substantially atmospheric pressure or to a suitable water or oil cushion and thus produce flow of the formation.

75 It is also apparent that utilizing the present invention with a water or oil cushion permits pumping the water or oil cushion into the perforated formation followed by an acid or sand frac.

This invention is not limited to the type of valve assem-

bly illustrated but may be practiced with any valve assembly which permits a full open hole and opens small valves controlling flow into the casing with movement of the production tubing relative to a member anchored in the well such as a packer. Any means which restrains opening of a valve and which is removed or overcome by movement of the tubing relative to the restraining member may be employed.

While auxiliary, desirable features have been illustrated, such as hold-down slips, these features are not necessary to the practice of the basic concept disclosed.

The foregoing disclosure and description of the invention is illustrative and explanatory thereof and various changes in the size, shape and materials, as well as in the details of the illustrated construction, may be made within the scope of the appended claims without departing from the spirit of the invention.

What is claimed is:

1. A well tool comprising, packer means including a tubular mandrel adapted to seal between said mandrel and the casing of a well in which the tool is run, means closing the lower end of the mandrel, said mandrel having a duct exposed to well fluids below the packer means, valve means carried by the mandrel and controlling flow through the duct for permitting well fluids below the packer means to enter the mandrel, means carried by the mandrel and maintaining the valve means in closed position while running the packer means, and means carried by the packer means responsive to setting of the packer means for rendering the maintaining means ineffective and opening the valve means.

2. A well tool comprising, packer means including a full open tubular mandrel adapted to be suspended from a production tubing and form a continuation thereof, a knock-out plug sealing the lower end of the mandrel, said packer means adapted to seal between said mandrel and the casing of a well in which the tool is run, said mandrel having a duct exposed to well fluids below the packer means, valve means carried by the mandrel and controlling flow through the duct for permitting well fluid below the packer means to enter the mandrel, means carried by the mandrel and maintaining the valve means in closed position while running the packer means, and means carried by the packer means responsive to setting of the packer means for rendering the maintaining means ineffective and opening the valve means.

3. A well tool comprising, packer means including a tubular mandrel, means closing the lower end of the mandrel, said packer means adapted to seal between the mandrel and the casing of a well in which the tool is run, said mandrel having a duct exposed to well fluids below the packer means, valve means carried by the mandrel and controlling flow through the duct for permitting well fluids below the packer means to enter the mandrel, means for balancing out the effect of well fluid pressure on the valve means to prevent formation of a hydraulic lock across the valve means, means carried by the mandrel and maintaining the valve means in closed position while running the packer means, and means carried by the packer means responsive to setting of the packer means for rendering the maintaining means ineffective and opening the valve means.

4. A well tool comprising a full open tubular mandrel adapted to be suspended from a production tubing and form a continuation thereof, a knockout plug sealing the lower end of the mandrel, means adapted to seal between the mandrel and the casing of a well in which the tool is run, said mandrel having a port therein exposed to fluid below the seal means, valve means controlling flow through the port, means on the exterior of the mandrel retaining said valve means in closed position, and means supported on the mandrel engaging the retaining means and rendering it ineffective upon downward movement of the mandrel relative to the seal means to open the valve means.

5. A well tool comprising hook wall packer means including a tubular mandrel and means surrounding the mandrel and movable relative thereto including seal means, means sealing the lower end of the mandrel, said hook wall packer means adapted to seal between the mandrel and the casing of a well in which the tool is run, a valve supporting member on the lower end of the mandrel and having at least one duct communicating at its inner end with the bore of the mandrel and at the outer end with the outside of said supporting member, a valve controlling the outer end of each duct carried by the supporting member, resilient means urging each valve toward closed position, a valve operating member on the lower end of said surrounding means, and a valve operating stem on each valve and extending toward and contacting said operating member to open the valve when actuated by relative motion between the operating member and mandrel during setting of the packer means.

6. A well tool comprising hook wall packer means including a tubular mandrel and means surrounding the mandrel and movable relative thereto including seal means, said hook wall packer means adapted to seal between the mandrel and the casing of a well in which the tool is run, a valve supporting member on the mandrel below the packer and having at least one duct communicating at its inner end with the bore of the mandrel and at the outer end with the outside of said supporting member, a valve controlling the outer end of each duct carried by the supporting member, resilient means urging the valve toward closed position, a valve operating member on the lower end of said surrounding means, a valve operating stem on each valve and extending toward and contacting said operating member to open the valve when actuated by relative motion between the operating member and mandrel during setting of the packer means, and a plug frictionally retained in and sealing the lower end of the mandrel bore.

7. In combination, hook wall packer means having a bore therethrough and adapted to be set in a well, a tubular mandrel adapted to be suspended from the lower end of a string of tubing and to be seated in the packer means bore, means closing the lower end of the mandrel, a valve assembly on the mandrel, seal means carried by one of the valve assembly and packer means and sealing therebetween when the mandrel is seated in the packer means, said mandrel having port means therein, said valve assembly having fluid conducting means communicating with said port means and having a terminus below said seal means when the mandrel is seated in the packer means bore, valve means controlling flow through the fluid conducting means, said packer means including actuating means, and means on the mandrel for engaging the actuating means and opening the valve means responsive to downward movement of the mandrel after said seal means has effected a seal between the mandrel and packer means.

8. In combination, hook wall packer means having a bore therethrough and adapted to be set in a well, a tubular mandrel adapted to be suspended from the lower end of a string of tubing and to be seated in the packer means bore, means closing the lower end of the mandrel to well fluids, a valve assembly on the mandrel seal means carried by at least one of the valve assembly and packer means, and sealing therebetween when the mandrel is seated in the packer means, said mandrel having port means therein, said valve assembly having fluid conducting means communicating with said port means and having a terminus below said seal means when the mandrel is seated in the packer means bore, valve means controlling flow through the fluid conducting means, said packer means including actuating means, means on the mandrel for engaging the actuating means and opening the valve means responsive to downward movement of the mandrel after said seal means has effected a seal between the mandrel and packer means, and means for re-

leasably latching the mandrel in seated position in the packer means.

9. In combination, hook wall packer means having a bore therethrough and adapted to be set in a well, a tubular mandrel adapted to be suspended from the lower end of a string of tubing and to be seated in the packer means bore, means closing the lower end of the mandrel to well fluids, a valve assembly on the mandrel, seal means carried by at least one of the valve assembly and packer means and sealing therebetween when the mandrel is seated in the packer means, said mandrel having port means therein, said valve assembly having fluid conducting means communicating with said port means and having a terminus below said seal means when the mandrel is seated in the packer means bore, valve means controlling flow through the fluid conducting means, said packer means including actuating means, means on the mandrel for engaging the actuating means and opening the valve means responsive to downward movement of the mandrel after said seal means has effected a seal between the mandrel and packer means, means for latching the mandrel in seated position in the packer means and for releasing the mandrel upon rotation thereof, said mandrel having second port means, second valve means controlling flow through the second port means, and means operable upon upward movement of the mandrel relative to the packer means to open the second valve means and thereby release any hydraulic lock across the packer means to permit ready rotation of the mandrel to release the mandrel.

10. As a sub-combination, a completion assembly adapted to be suspended from the lower end of a string of tubing and to be seated in a hook wall packer previously landed in a well comprising, a tubular mandrel, means closing the lower end of the mandrel to well fluids, said mandrel having a port extending therethrough a valve supporting member on the mandrel and having fluid-conducting means therein communicating with said port and with the outside of said supporting member, valve means controlling the fluid-conducting means, resilient means urging the valve toward closed position, and valve actuator means depending from the supporting member and adapted to be actuated by engagement with said packer as the tool is landed in said packer, said valve actuator when moved relative to said valve supporting member during landing of the packer moving said valve to open position against the force exerted by said resilient means.

11. As a sub-combination, a completion assembly adapted to be suspended from the lower end of a string of tubing and to be seated in a hook wall packer previously landed in a well comprising, a tubular mandrel, means closing the lower end of the mandrel to well fluids, said mandrel having a port extending therethrough, a valve supporting member on the mandrel and having fluid-conducting means therein communicating with said port and with the outside of said supporting member, valve means controlling the fluid-conducting means, resilient means urging the valve means toward closed position, valve actuator means depending from the supporting member and adapted to be actuated by engagement with said packer as the tool is landed in said packer, said valve actuator when moved relative to said valve supporting member during landing of the packer moving said valve to open position against the force exerted by said resilient means, second port means in the mandrel, second valve means carried by the supporting means controlling flow through said second port means, said second valve means operable upon upward movement of the mandrel relative to the valve support means to open the second port means.

12. As a sub-combination, a tubular mandrel having a port therein, means closing the lower end of the mandrel, a valve supporting member fixed to the tubular mandrel and having fluid-conducting means communicating with

said port and with the outside of said supporting member, valve means controlling the fluid conducting means, means urging the valve means toward closed position, a valve opening stem on said valve means having at least a portion extending outside of said supporting member, and a valve-operating housing adapted to be attached to a packer slip assembly and engaging the stem during setting of the packer to open the valve.

13. A well tool comprising, a tubular mandrel having port means in the side wall thereof, means closing the lower end of the mandrel to well fluids, valve means on the mandrel in fluid communication with said port means for permitting well fluids to enter the mandrel, means on the mandrel to maintain the valve means in closed position while running the mandrel, and means adapted to be anchored to the wall of a well for rendering the maintaining means ineffective and opening the valve means upon further downward movement of the mandrel.

14. A well tool comprising, a tubular mandrel having port means in the side wall thereof, means closing the lower end of the mandrel to well fluid, valve means on the exterior of the mandrel in fluid communication with said port means for permitting well fluids to enter the mandrel, means on the mandrel to maintain the valve means in closed position while running the tool, means carried by the mandrel for balancing out the effect of well fluid pressure on the valve means to prevent formation of a hydraulic lock across the valve means, and means adapted to be anchored to the wall of a well for rendering the maintaining means ineffective and opening the valve means upon further downward movement of the mandrel.

15. A well tool comprising, a full open tubular mandrel adapted to be suspended from a production tubing and form a continuation thereof, a knock-out plug sealing the lower end of the mandrel, means adapted to seal between the mandrel and the casing of a well in which the tool is run, fluid-conducting means in the mandrel exposed to fluid below the seal means, valve means controlling flow through the fluid-conducting means, means including an actuator rod on the exterior of the mandrel and resilient means urging the actuator rod towards valve-closing position for retaining the valve means in closed position, and means carried by the mandrel engaging the actuator rod and moving it to valve-opening position upon downward movement of the mandrel relative to the seal means to open the valve means.

16. A testing and production apparatus comprising, hook wall packer means including a tubular mandrel and means surrounding and movable relative to said mandrel including seal means adapted to seal between the mandrel and the wall of a well in which the tool is run, means closing the lower end of the mandrel, a valve support member surrounding the mandrel and fixed thereto on its lower end, said valve support member having at least one opening therethrough, each opening being parallel to the axis of the mandrel and each opening having a lower valve guide portion and an upper duct portion, a valve overlying and controlling each of said duct portions and having a stem extending downwardly through the duct portion and through and below the corresponding guide portion, means providing a seal between said stem and the guide portion, spring means for urging said valve downwardly to seal the upper end of its duct portion, said mandrel having a port therein communicating with said opening intermediate said valve and seal means, and a valve-operating housing fixed to said surrounding means and underlying the lower end of the stems whereby when the tubing is moved downwardly with respect to said surrounding means to set the packer, the stems will abut said housing and open the valves.

17. The tool of claim 16 wherein the means closing the lower end of the mandrel is a plug in the bore of the mandrel which is frictionally retained in the mandrel but

is dischargeable therefrom when forces within the mandrel exceed the pressure outside of said mandrel.

18. Apparatus comprising, a hook wall packer including a mandrel and means slidably mounted on the mandrel for engaging the wall of a well, a valve support member surrounding the mandrel and fixed thereto below the engaging means, said valve support member having at least one opening therethrough, each opening being parallel to the axis of the mandrel and each opening having a lower valve guide portion and an upper duct portion, a valve overlying and controlling each of said duct portions and having a stem extending downwardly through the duct portion and through and below the corresponding guide portion, means providing a seal between said stem and the guide portion, spring means for urging said valve downwardly to seal the upper end of its duct portion, said mandrel having a port communicating with said opening intermediate said valve and seal means, a

5 valve operating housing fixed to said engaging means and underlying the lower end of the stems whereby when the mandrel is moved downwardly with respect to the engaging means, the stems will abut said housing and open the valves, and a plug in the bore at the lower end of the mandrel sealing the mandrel, said plug being frictionally retained in the mandrel but being dischargeable therefrom from forces therein exceeding the pressure outside of said mandrel.
